UNITED STATES PATENT OFFICE

96,123

DESIGN FOR A CHAIR OR THE LIKE

Julian Kowalski, Chicago, Ill.

Application April 13, 1935, Serial No. 56,354

Term of patent 7 years

To all whom it may concern:

Be it known that I, Julian Kowalski, a citizen of the United States, residing at Chicago, in the county of Cook and State of Illinois, have invented a new, original, and ornamental Design for Chairs or the like, of which the following is a specification, reference being had to the accompanying drawing, forming a part thereof.

In the drawing:

The figure is a perspective diagrammatic view of a chair showing my design.

The dominant feature of my design resides in the upholstery applied to the chair, as shown in full lines in the figure, the conventional chair being shown in dotted lines.

I claim:

The ornamental design for a chair or the like, as shown and described.

In witness whereof, I hereunto subscribe my name, this 11th day of April, 1935.

JULIAN KOWALSKI.
